[57] **CLAIM**

The ornamental design for a unified footpiece clamp for computer paper margin stripper, as shown and described.

DESCRIPTION

FIG. 1 is a right front perspective view of a unified footpiece clamp for computer paper margin stripping showing a first form of my new design;

FIG. 2 is a left side elevation thereof;

FIG. 3 is a front elevational view;

FIG. 4 is a right side elevation;

FIG. 5 is a top plan view;

FIG. 6 is a rear elevational view;

FIG. 7 is a bottom plan view;

FIG. 8 is a left front perspective view of a unified footpiece clamp for computer paper margin stripping showing another form of my new design;

FIG. 9 is a right side elevation thereof;

FIG. 10 is a front elevational view thereof;

FIG. 11 is a right side elevation thereof;

FIG. 12 is a top plan view thereof;

FIG. 13 is a rear elevational view thereof; and,

FIG. 14 is a bottom plan view thereof.

The broken lines in FIGS. 1 and 8 are for illustrative purposes only and form no part of the claimed design.
